Primary Examiner — Holly Baynham*(74) Attorney, Agent, or Firm* — Sheridan Ross P.C.**CLAIM**

The ornamental design for a cap for a utility box, as shown and described.

DESCRIPTION

FIG. 1 is a front perspective view of a cap for a utility box;
 FIG. 2 is a top plan view thereof;
 FIG. 3 is a right elevation view thereof;
 FIG. 4 is a front elevation view thereof;
 FIG. 5 is a bottom plan view thereof;
 FIG. 6 is a rear elevation view thereof; and,
 FIG. 7 is a left elevation view thereof.

The broken lines showing structure are for the purposes of illustrating environment and form no part of the claimed design.
